(57) **CLAIM**

The ornamental design for a stroller handle cover, as shown and described.

DESCRIPTION

FIG. 1 is a front view of the stroller handle cover;
FIG. 2 is a back view of the stroller handle cover;
FIG. 3 is a left side view or right side view of the stroller handle cover;

FIG. 4 is a top view of the stroller handle cover;
FIG. 5 is a bottom view of the stroller handle cover; and,
FIG. 6 is a perspective view of the stroller handle cover mounted on a stroller.

The broken line showing of the stroller is for illustrative purposes only and forms no part of the claimed design.
